UNITED STATES PATENT OFFICE.

FREDERICK H. PERRY, OF BEVERLY, MASSACHUSETTS, ASSIGNOR TO UNITED SHOE MACHINERY COMPANY, OF PATERSON, NEW JERSEY, A CORPORATION OF NEW JERSEY.

WELT-SEWING MACHINE.

1,079,436.

Specification of Letters Patent. Patented Nov. 25, 1913.

Application filed May 2, 1910. Serial No. 553,866.

To all whom it may concern:

Be it known that I, FREDERICK H. PERRY, a citizen of the United States, residing at Beverly, in the county of Essex and State of Massachusetts, have invented certain new and useful Improvements in Welt-Sewing Machines; and I do hereby declare the following to be a full, clear, and exact description of the invention, such as will enable others skilled in the art to which it appertains to make and use the same.

The present invention relates to welt sewing machines, and more particularly to means for holding the end of the welt while it is being attached to the upper and insole at the beginning of the sewing operation.

In operating welt sewing machines the operator usually holds the end of the welt against the shoe at the beginning of the sewing operation, so that the welt is fed along with the shoe during the formation of the first few stitches. When the end of the welt is thus held the seam must be started at some distance from the end of the welt, with a resulting waste of welting. It has been proposed to avoid this waste by providing devices for holding the end of the welt during the formation of the first few stitches so that the seam may be started close to the end of the welt. These devices as heretofore constructed have required special manipulation and attention on the part of the operator in throwing them into operation, with a resulting waste of time and decrease in the production of the machine. These devices have also been so constructed and arranged that the welt holder is moved with the shoe during the feed by its engagement with the shoe. This increases the resistance offered to the movement of the shoe by the feeding awl or other feeding device, which is liable to result in an imperfect or inaccurate feed of the shoe.

It is accordingly the object of the present invention to provide devices for holding the end of the welt at the beginning of the sewing operation which are thrown into and out of operation without requiring any special care or attention on the part of the operator, and which do not offer any resistance to the feed of the shoe by the feeding devices.

To these ends one feature of the invention contemplates the provision in a welt sewing machine of a welt holder which may be thrown into operation in starting the machine. This feature of the invention in its broader aspects contemplates the employment of any suitable construction and arrangement of devices through which the welt holder may be engaged with the end of the welt upon the starting of the machine either directly by the operator or automatically by mechanism which is rendered active at the beginning of the sewing operation.

In the simplest and most desirable form of the invention which has been devised, the welt holder is engaged with the end of the welt through connection with the starting treadle, so that the operator in operating the treadle to start the machine also brings the welt holder into position to hold the end of the welt, and this arrangement forms a further feature of the invention. With this construction, no additional attention or manipulation of parts on the part of the operator is required at the beginning of the sewing operation, and the operator is relieved of the duty of holding the end of the welt, so that the sewing of the shoe may be more rapidly performed, with less care on the part of the operator, and with less danger of injury to them.

A further feature of the invention contemplates the provision in a welt sewing machine of a device for engaging the end of the welt and holding it at the beginning of the sewing operation, which is actuated to move with the shoe during the feed independently of its engagement with the shoe. The welt holding devices do not therefore offer any resistance to the advance of the shoe by the feeding devices, but on the contrary may assist in feeding the shoe at the beginning of the sewing operation, and until the end of the welt has been secured to the shoe by the stitch forming mechanism. For the sake of simplicity of construction it is preferred to move the welt holding device in the direction of the feed of the shoe through connection with the shoe feeding mechanism, and this arrangement forms a further feature of the invention.

In addition to the feature above out-

lined, the invention includes certain further features and combinations of parts which will be hereinafter explained and referred to in the claims, the advantages of which 5 will be apparent to those skilled in the art.

In the drawings the invention is illustrated as embodied in an attachment applied to the well-known Goodyear welt sewing machine, but it will be understood that the 10 invention is not confined in its application to an attachment of this kind, but may be embodied in attachments for other forms of welt sewing machines, or may be otherwise incorporated in the Goodyear or other 15 machines.

The various features of the invention will be understood from an inspection of the accompanying drawings, and the following detailed description of the construction 20 shown therein.

In the drawings Figure 1 is a left-hand side elevation of the Goodyear welt and turn sewing machine having an attachment embodying the invention applied thereto; 25 Fig. 2 is a horizontal sectional view on line 2—2, Fig. 1; Fig. 3 is a partial side elevation showing the welt holder advanced into position to engage the welt; Fig. 4 is a sectional plan view on line 4—4, Fig. 3, showing the parts in the position which they assume as the machine is thrown into operation; Fig. 5 is a similar view showing the parts in the position which they occupy 30 after the first feeding movement of the shoe; Fig. 6 is a sectional view on line 6—6, Fig. 4; Fig. 7 is a detail plan view showing the rear end of the carrier for the welt holder; and Fig. 8 is a detail plan view of the front 35 end of the carrier.

Referring to the drawings, 1 indicates the 40 frame of the machine, 2 the gage or work support, 3 the welt guide, 4 the needle, 5 the looper, 6 the feed point, and 7 the feed slide, these parts being constructed and arranged in the same manner and operated by 45 the same mechanisms as the corresponding parts of the well-known Goodyear welt and turn machine, which is disclosed in the patent to French and Meyer, No. 412,704, 50 October 8, 1889. The machine is also provided with means for engaging the end of the welt which projects through the welt guide, and holding it in proper relation to the shoe at the beginning of the sewing 55 operation, and until it is attached to the shoe by the stitch forming mechanism. In the construction shown, the means for holding the end of the welt at the beginning of the sewing operation comprises a finger 8 60 which is provided at its forward end with a point 9 adapted to penetrate the end of the welt and hold it in contact with the shoe. The rear end of the welt holding finger is adjustably secured in a split boss 10 formed

at the front end of a holder carrying arm 65 11, so that the welt engaging point 9 may be conveniently adjusted to properly engage and position the welt. In order that the welt holding finger may move with the shoe as the shoe is fed at the beginning of the 70 sewing operation, the carrying arm 11 is mounted to swing about a pivot 12, and in order that the finger may be readily engaged with and disengaged from the welt at the proper times, the pivot 12 is carried upon 75 a slide 13 which is mounted in a supporting bracket 14. The slide 13 is normally held in retracted position so that the welt holding finger is out of engagement with the welt, by a spring 15. The holder carrying arm 11 80 is held in normal position against an adjustable stop screw 16 upon the slide 13, by a spring pressed plunger 17 (Fig. 7). This plunger engages the rear end of a lever 18 which is pivoted upon the slide 13, and is 85 provided at its forward end with an adjusting screw 19 arranged to engage a pin 20 on the arm 11. By these devices the spring 21 back of the pin 17 acts to hold the welt engaging finger in proper position to engage 90 the welt when the slide 13 is advanced, yields to allow the finger to move in the direction of feed with the shoe, and acts to return the finger to normal position upon the slide when the slide is retracted and the 95 finger is disengaged from the welt. The lever 18 also acts as a latch for connecting the slide 13 with its actuating lever, and for disconnecting it therefrom when the welt holding finger moves in the direction of the 10 feed, as will be more fully explained hereafter.

The slide 13 is advanced to engage the welt holding finger with the welt by an actuating lever 22, one arm of which carries a laterally projecting pin 23 provided with a shoulder 24 arranged to engage the rear end of the lever 18. The actuating lever is held normally in retracted position by a spring 25 and is operated to advance 10 the slide 13 through a rod 26. In order that the welt holder may be engaged with the welt prior to the initial operation of the sewing mechanism, and without requiring any attention on the part of the operator, 11 the rod 26 is preferably connected with the starting treadle which is depressed by the operator in starting the machine. This treadle is held in its depressed position by the operator during the sewing operation, 1 and is not released until the sewing of the shoe has been completed. In order that the welt holding finger may be disengaged from the welt after the end of the welt has been secured to the upper and insole by the initial 1 operation of the stitch forming devices, means are provided for disconnecting the slide 13 from its actuating lever 22. For

the sake of simplicity in construction, the slide is so connected with its actuating lever that it is disconnected therefrom by the movement of the welt holder in the direction of the feed of the shoe.

In the construction shown, the lever 22 is connected with the slide 13 through the lever 18 so that the slide is advanced to engage the welt holder with the welt when the lever 22 is actuated in depressing the starting lever of the machine. The slide is held in advanced position with the welt holder in engagement with the welt during the initial operation of the stitch forming mechanism in drawing the first loop of thread through the work and during the first feed of the work. During the feed of the work the welt holder moves with the work in the direction of feed, the welt holding arm 11 swinging about the pivot 12. During this movement of the carrier arm 11 the pin 20 acts to rock the lever 18 against the tension of the spring 21 so that the rear end of the lever is disengaged from the shoulder 24 on the actuating lever 22. This disconnects the slide 13 from the actuating lever so that the slide may be retracted by the spring 15 to disengage the welt holder from the welt. When the welt engaging point 9 is disengaged from the welt by the rearward movement of the slide 13, the spring 21 acts through the lever 18 to return the holder carrying arm 11 to normal position against the stop 16 preparatory to the next movement of the holder into engagement with the welt at the beginning of the sewing operation upon the succeeding shoe.

The welt engaging finger may be moved in the direction of the feed during the initial feed of the shoe by its engagement with the shoe without departing from the broader features of the invention embodied in the construction thus far described. It is preferred, however, to provide mechanism for moving the welt holder in the direction of feed during the feed of the shoe, since with such construction the welt will be held in a more reliable and uniform manner, and there will be less danger of an improper feed of the welt or shoe. In accordance with this feature of the invention means are accordingly provided for actuating the welt holder from the feed mechanism of the machine. With this construction the proper movement of the welt holder in unison with the feeding movement of the shoe is insured. This construction also enables the connections to be conveniently arranged so that the adjustments in the feed mechanism for different lengths of stitch result in corresponding variations in the movement imparted to the welt holder by the feed mechanism.

In the construction shown, the devices for

connecting the feed mechanism of the machine with the welt holding device so that the welt holding device is moved in the direction of the feed of the shoe by the feed mechanism, comprises a rod 27 adjustably clamped in a split bearing 28 which is secured to the feed slide 7. The front end of this rod is arranged to engage the end of an arm 29 which is pivoted on the front end of the holder carrying arm 11 and is held normally in position against a stop pin 30 by a spring pressed pin 31. When the slide 13 is advanced to engage the welt holding finger with the welt, the rod 27 will be approximately in the position indicated in Fig. 4, and as the slide advances the front end of the arm 29 will ride under the rod, the spring pin 31 yielding to allow such movement of the arm. When the feed slide is retracted, preparatory to the initial feed of the shoe, the end of the rod 27 passes from above the arm 29 so that the arm may move up into normal position under the influence of the spring pin 31. When in this position the front end of the arm is in the path of the rod 27, so that during the initial feed of the shoe the end of the rod engages the arm and moves the welt holder to feed the welt with the shoe. In order that the welt engaging finger may be maintained in engagement with the welt until the forward feed of the shoe is completed without requiring a fine or accurate adjustment of the devices for disengaging the slide 13 from its actuating lever, the engaging faces of the rod 27 and the arm 29 are preferably provided with interlocking teeth 32. These teeth act to retain the welt holding finger in engagement with the welt after the slide 13 has been disconnected from its actuating lever, and prevent the retraction of the slide until the feed slide starts on its return movement. When the feed slide starts to return, the rod 27 moves away from the arm 29, thus disengaging the teeth, so that the welt holding finger is retracted by the spring 15.

While it is preferred to employ the specific construction and arrangement of parts shown and described, it will be understood that this construction and arrangement is not essential, except so far as referred to in the claims, and may be varied and modified without departing from the broader scope of the invention.

Having explained the nature and object of the invention, and specifically described one construction in which it may be embodied, what I claim is:

1. A welt sewing machine, having, in combination, stitch forming mechanism, a welt guide, an independently movable welt holder for holding the end of the welt in the rear of the sewing point, and devices for throwing the welt holder into operation in start-

ing the stitch forming mechanism, substantially as described.

2. A welt sewing machine, having, in combination, stitch forming mechanism, an independently movable welt holder for holding the welt in the rear of the sewing point, and connections between the starting mechanism of the machine and the welt holder for engaging the welt holder with the end of the welt in starting the stitch forming mechanism, substantially as described.

3. A welt sewing machine, having, in combination, stitch forming mechanism, a welt guide, a welt holder for holding the end of the welt against the shoe, devices for throwing the welt holder into operation in starting the stitch forming mechanism, and mechanism for automatically throwing the welt holder out of operation after the end of the welt has been attached to the shoe, substantially as described.

4. A welt sewing machine, having, in combination, stitch forming mechanism, a welt holder movable in the direction of the feed, actuating devices for engaging the holder with the end of the welt, and means for disconnecting the holder and actuating devices by the movement of the holder in the direction of the feed, substantially as described.

5. A welt sewing machine, having, in combination, stitch forming mechanism, a welt holder movable in the direction of the feed, an actuating device for engaging the welt holder with the end of the welt, a latch connecting the holder and actuating device, and means for disengaging the latch by the movement of the holder with the shoe, substantially as described.

6. A welt sewing machine, having, in combination, stitch forming mechanism, a welt holder movable in the direction of the feed, a spring for retracting the welt holder, an actuating device for advancing the holder into engagement with the end of the welt, a latch for retaining the holder in engagement with the welt, and means for disengaging the latch after the end of the welt has been connected with the shoe, substantially as described.

7. A welt sewing machine, having, in combination, stitch forming mechanism, a welt holder for holding the end of the welt in the rear of the sewing point, and mechanism for retaining the holder in engagement with the welt and moving it with the shoe independently of this engagement with the shoe during at least one cycle of operations of the machine, substantially as described.

8. A welt sewing machine, having, in combination, stitch forming mechanism, a welt guide, a welt holder for holding the end of the welt in the rear of the sewing point, and

mechanism for moving the holder with the shoe independently of its engagement therewith, substantially as described.

9. A welt sewing machine, having, in combination, stitch forming mechanism, mechanism for holding and feeding the welt during the initial operation of the stitch forming mechanism, and means for rendering the welt holding and feeding mechanism inactive during the continuance of the sewing after the end of the welt has been attached to the shoe, substantially as described.

10. A welt sewing machine, having, in combination, stitch forming mechanism including means for feeding the shoe, a welt guide, a welt holder for holding the end of the welt in the rear of the sewing point, and connections between the shoe feeding means and holder, for moving the holder with the shoe in the direction of feed, substantially as described.

11. A welt sewing machine, having, in combination, stitch forming mechanism, an independently movable welt holder for holding the welt in the rear of the sewing point, and mechanism for actuating the holder to hold the end of the welt upon the starting of the stitch forming mechanism, substantially as described.

12. A welt sewing machine, having, in combination, stitch forming mechanism, a welt holder, devices for connecting the welt holder with the starting mechanism of the machine for engaging the welt holder with the end of the welt, and means for automatically disengaging the welt holder from the welt after the end of the welt has been attached to the shoe, substantially as described.

13. A welt sewing machine, having, in combination, stitch forming mechanism including means for feeding the shoe, a welt holder, actuating devices for engaging the welt holder with the end of the welt, means for disengaging the welt holder from the actuating devices by its movement with the shoe during the feed, and means for retaining the welt holder in engagement with the welt until the feeding movement of the shoe has been completed, substantially as described.

14. A welt sewing machine, having, in combination, stitch forming mechanism including means for feeding the shoe, a welt holder movable in the direction of the feed, actuating devices for engaging the welt holder with the end of the welt, connections between the feeding mechanism and the holder for moving the holder with the shoe during the feed and retaining the welt holder in engagement with the shoe, and means for disconnecting the welt holder and actuating devices by its movement with the shoe, substantially as described.

15. A welt sewing machine, having, in combination, stitch forming mechanism, a welt holder movable toward and from the shoe and in the direction of the feed of the shoe, an actuating device, devices for connecting the actuating device with the starting treadle of the machine, and means for disconnecting the actuating device and holder by the movement of the holder with the shoe, substantially as described.

Correction in Letters Patent No. 1,079,436.

It is hereby certified that in Letters Patent No. 1,079,436, granted November 25, 1913, upon the application of Frederick H. Perry, of Beverly, Massachusetts, for an improvement in "Welt-Sewing Machines," an error appears in the printed specification requiring correction as follows: Page 4, line 16, strike out the words "against the shoe"; and that the said Letters Patent should be read with this correction therein that the same may conform to the record of the case in the Patent Office.

Signed and sealed this 23rd day of December, A. D., 1913.

[SEAL.]

J. T. NEWTON,

Acting Commissioner of Patents.
